TROLLEY AND CURRENT COLLECTOR
MEANSHarrison J. L. Frank and Joseph A. Messing,
Detroit, Mich.

Original application August 26, 1935, Serial No. 37,953, now Patent No. 2,117,552, dated May 17, 1938, which is a division of applications Serial No. 727,516, May 25, 1934, now Patent No. 2,018,016, dated October 22, 1935, and Serial No. 20,113, May 6, 1935, now Patent No. 2,052,972, dated September 1, 1936. Divided and this application April 16, 1938, Serial No. 202,402

4 Claims. (Cl. 200—115.5)

This invention relates to current collector means particularly adapted for use in connection with the stationary bus duct of a current distributing system such as the one previously disclosed in Patent No. 2,018,846 of October 29, 1935. The instant application is a division of our prior application Serial No. 37,953 filed August 26, 1935, now Patent No. 2,117,552 of May 17, 1938, which in turn is a division of applications Serial No. 727,516 filed May 25, 1934, now Patent No. 2,018,016 of October 22, 1935, and Serial No. 20,113 filed May 6, 1935, now Patent No. 2,052,972 of September 1, 1936.

The instant application relates specifically to collector means for withdrawing current from slotted tube bus duct.

The principal objects of the present invention are to provide collector means which shall be of light weight and small size and which have a high degree of economy of manufacture and efficiency of operation.

Objects of the invention, which relate more distinctly to novel and important details of manufacture of the collector means shown and described herein, will be readily apparent upon reference to the following detailed descriptive matter relating to the appended drawing.

Referring to the drawing, it will be seen that— Fig. 1 shows in top plan view a plug collector;

Fig. 2 is a side elevational view of the same;

Figs. 3 and 4 are end elevational views of the same as if taken from planes 3—3 and 4—4 respectively of Fig. 1.

In the figures there is shown a plug collector which is more particularly adapted for stationary use with a duct and is not normally intended to be moved along the duct as is the case with a trolley type collector. In this construction, the collector includes an elongated insulating base 120 having fuse clips 121 thereon, between pairs of which are disposed cartridge fuses 122. Connected to the pairs of those clips are two end brushes 123 and a center brush 124, the end brushes 123 being formed to engage the bus bars of the vertical sides of the duct and the center brush 124 being formed to engage the bus bar on the horizontal side or top of the duct, the center brush 124 projecting a considerable distance above the remaining parts of the collector. The base is supported by the vertical parts 126 of two frame plates 127 between which parts 126 it is disposed, and these frame plates are flanged downwardly at their edges, as indicated at 128. It is observed that the construction is such that

the base 120 is diagonally disposed with respect to the frame plates as a whole, for reasons to be described, and that the edges of the frame plates, at the corners most remote from the base, are provided with upwardly projecting vertical stops 129, also for reasons to be described. The parts 126 of the plates, diagonally remote from the stops 129, have elongated notches 130, also for reasons to be described.

Further, secured to and disposed under the under surface of the frame plates are small plates 131 having upwardly projecting parts 132 which are thus rendered resiliently mounted with respect to the frame plates. The frame plates as a whole are rigidly secured to a block 133 in turn rigidly secured to the end of a handle 134. Conductors 135, connected to the pairs of fuse clips 121 in proper fashion, pass downwardly through the space between the vertical parts 126 of the frame plate and down through the bore of the handle 134 to the load consuming device. To the block 133 are detachably secured, as by screws 137, plates 138 which conceal the wiring on the under surface of the base 120, and these plates are underlapped by plates 139, welded to the frame plates 127, completing the concealing of the wiring.

The manipulation of the collector of Figs. 1—4 is as follows:

When the collector is to be inserted into a duct, the base 120 and parts 121, 122, 123, and 124, thereon, are inserted into the opening in the bottom of the duct; the frame plates 127 will then be somewhat askew of the duct. The collector will not yet be interlocked to the duct because of the fact that all of the parts of the collector, in the duct, are in line with the opening. The collector is then rotated a few degrees so that the base will be askew of the duct and will straddle the opening thereof, to interlock the collector to the duct. Elongated slots 130 in the vertical portions 126 of the frame plates 127 permit rotation of the collector as a whole with respect to the duct, the duct flanges being cleared through these slots.

After such rotation, the resilient brush 124, engaging the bottom of the upper bus bar, will bias the collector against the upper edges of the flanges at the bottom opening of the duct, with the frame plates in line with the duct. Stops 129 limit the degree of rotation of the collector as a whole with respect to the duct, upon insertion, to prevent injury to the brushes 123. After rotation is accomplished, the brushes 123 on the

base will engage the side bus bars for proper contact, and with brush 124, already in engagement with the top bus bar, will complete the electrical connections desired.

- 5 For removal of the collector, it is necessary to rotate the collector back to its pre-insertion position, whereupon the collector may be lowered out of the duct.

It is noted that collectors of Figs. 1-4 are in 10 the nature of removable wall or closure plates for parts of the open bottom of the duct, and that they carry the fuses 122 inside the duct; they thus cooperate with the duct to form an enclosed conduit inside which are provided and enclosed the fuses, these being on what might well be termed removable wall portions (the collectors) for the duct. Also, since the collectors must be removed from the duct before the fuses can be manipulated, an automatic interlock, to 20 prevent manipulation of live fuses, is effected.

We claim:

1. A detachable connector for use with a duct having a slotted wall on whose sides are bus bars comprising a handle having a base and a 25 head, the latter being insertable into the duct through the slot and having contacts engaging the side bus bars of the duct when inserted into the duct and rotated therein to straddle the slot, the base remaining outside the duct and 30 engaging the slotted wall so that the latter is clamped between the head and the base.

2. A detachable connector for use with a duct having a slotted wall on whose sides are bus bars comprising a handle having a base and a 35 head, the latter being insertable into the duct

through the slot and having contacts engaging the side bus bars of the duct when inserted into the duct and rotated therein to straddle the slot, the base remaining outside the duct and engaging the slotted wall so that the latter is clamped between the head and the base, and fuses on the head and disposed within the duct.

3. A detachable connector for use with a duct having a slotted wall on whose sides are bus bars comprising a handle having a base and a 1 head, the latter being insertable into the duct through the slot and having contacts engaging the side bus bars of the duct when inserted into the duct and rotated therein to straddle the slot, the base remaining outside the duct and engaging the slotted wall so that the latter is clamped between the head and the base, the collector 1 forming a removable closure for that part of the slot of the duct near which are contacts.

4. A detachable connector for use with a duct 2 having a slotted wall on whose sides are bus bars comprising a handle having a base and a head, the latter being insertable into the duct through the slot and having contacts engaging the side bus bars of the duct when inserted into the 2 duct and rotated therein to straddle the slot, the base remaining outside the duct and engaging the slotted wall so that the latter is clamped between the head and the base, the collector 3 forming a removable closure for that part of the 3 slot of the duct near which are contacts, and fuses on the head and disposed within the duct.
